Attorney.

UNITED STATES PATENT OFFICE.

JAMES H. LA PEARL, OF KOKOMO, INDIANA.

WINDOW-SHADE-ROLLER HOLDER AND ADJUSTER.

1,411,174.

Specification of Letters Patent. Patented Mar. 28, 1922.

Application filed March 28, 1921. Serial No. 456,460.

To all whom it may concern:

Be it known that I, JAMES H. LA PEARL, a citizen of the United States, residing at Kokomo, in the county of Howard and State of Indiana, have invented new and useful Improvements in Window-Shade-Roller Holders and Adjusters, of which the following is a specification.

The object of this invention is to provide 10 a window shade holder which is adapted to be adjusted to any vertical position of the window within the range of the device, in order to shut out the direct rays of the sun, while providing for ventilation either be- 15 low or above the shade.

A further object is to provide easy means for changing the range of vertical adjustment of the shade holder, from a part only, to the entire vertical length of the window.

20 The object also is to provide an exceedingly simple device which will be inexpensive to manufacture, easy to install, even by inexperienced persons, and one that is durable and not likely to get out of order in 25 use.

I accomplish the above and other objects which will hereinafter appear, by the mechanism illustrated in the accompanying drawing, in which—

30 Fig. 1 is a perspective view of my invention operatively applied to a window, and in position at the top of the frame. Fig. 2 is a front elevation of a window on a smaller scale than that of Fig. 1, but showing 35 the entire window with the shade and support in about the same position as shown in Fig. 1, in which the shade is covering the major upper portion of the window. Fig. 3 is a like view of the window showing the shade 40 roller holder below the parting rail of the lower sash, and the shade entirely opposite the lower sash. Figs. 4 and 5 are details showing the construction of the eyelet by 45 which the holding and adjusting cord of the shade roller holder is fastened to the latter and Fig. 6 is a cross section of the roller holder showing the construction of the clamping band thereon.

Like characters of reference indicate like 50 parts in the several views.

The shade 7 is mounted on a spring-actuated roller (not shown) having a round pin 8 at one end of the roller and a flat-sided one 9, at the other; all of usual construction. Vertical brackets 10 and 11, to 55 support pins 8 and 9, respectively, are

formed out of strap metal. The lower ends of said brackets are bent out at right angles to form guiding ears 12, 12, which are perforated, and through the perforations vertical guide-wires 13, 13, are threaded, in the manner shown. The wires are fastened to the respective screw-eyes 14, 14', screwed into the top 15, of the window frame, and also to screw-eyes 16, 16, screwed into the 65 sides of the frame, and the wires, after being threaded through the perforations of said ears, are drawn taut between their screw-eyes.

The straps from which the brackets 10 and 11 are formed are bent at right angles at the tops of the brackets in the opposite direction from that of their respective ears and are continued to form suitable spacer-members 17 and 18, which are joined by a 75 connecting bar 19, made out of the same strap material.

The spacer-members 17 and 18, are adjustably secured to the connecting bar 19, by loops 20, 20, formed of strap metal bent 80 around the parts in the manner shown in Fig. 6, with the ends of the strap bent out at right angles to the body-portion forming parallel ears which are drawn together by tightening a nut on a screw-bolt 21, passed 85 through holes in said ears. This forms a clamping band by which given adjustments of the spacer-members and connecting bar are held.

Holes are formed through the spacer-members 17 and 18, preferably as close to their respective brackets as possible in order to secure a direct support, and in these holes the eyelets 22, 23, are fastened. A cord, wire, or other suitable flexible cable 24 90 has one end fastened to the eyelet 22. It is then threaded through the screw-eye 14 and carried thence across and through the screw-eye 14' from which a length sufficient to come within easy reach of a person desiring 100 to raise and lower the shade, and for fastening same to a suitable bracket 25, depends from the screw-eye 14'. A second cable 26 is fastened to the eyelet 23, and is passed thence through the screw-eye 14' from which 105 a length equal to that of cable 24 depends. The ends of the two depending cable lengths may be tied together if desired, but at any rate, they are manipulated together to raise and lower my roller supporting device with roller and shade attached. The latter parts are in fact suspended from

screw-eyes 14, 14' by cables 24 and 26; their weight will move them to the bottom of the window or as far as the guide wires 13, 13, and lower screw-eyes 16, 16, will let them 5 go, when the cables are released, and any desired position is retained by fastening the cables to bracket 25. The shade is rolled upon the roller and unrolled therefrom to the desired length in the usual manner, my 10 invention having only to do with the vertical adjustment of the roller itself.

While I have described the best embodiment of my invention now known to me it is obvious that many minor changes may be 15 made and I therefore do not desire to be limited any more than is required by the appended claim.

I claim:

In a window-shade roller holder, a pair of 20 brackets formed out of strap metal in a separate piece for each bracket which is bent outwardly at the lower ends of the brackets to form guide-ears, said ears being perforated, and said strap pieces being bent in-

wardly at the upper ends of the brackets to 25 form spacer-members, a connecting bar lapping the ends of said spacer-members, clamping loops binding the lapped ends together, a pair of screw-eyes attached to the window frame one above each bracket, a 30 pair of screw-eyes attached each to a side of the window frame at the lower limit of travel of the shade-roller holder, guide wires respectively passing through the perforated ears and stretched between and fastened to 35 vertical pairs of said screw-eyes, a cable attached to one end of the holder and passing thence up and through the nearest screw-eye above the bracket, a second cable attached to the other end of the holder and passing 40 up and through the nearest screw-eye over that end and then across and through the last-named screw-eye, and means for making the depending ends of the two cables fast.

Signed at Indianapolis, Indiana, this the 25 day of March, 1921.

JAMES H. LA PEARL.
